(57) **CLAIM**

The ornamental design for a ligature resistant swinging door as shown and described.

DESCRIPTION

FIG. 1 is a side isometric view of a ligature resistant swinging door in accordance with the new design; FIG. 2 is a first side elevational view thereof; FIG. 3 is a second side elevational view thereof; FIG. 4 is a first end elevational view thereof; FIG. 5 is a second end elevational view thereof; FIG. 6 is a top plan view thereof; FIG. 7 is a bottom plan view thereof; and, FIG. 8 is a side isometric view of the ligature resistant swinging door of FIG. 1 shown in its intended environment. The broken lines of FIG. 8 are for the purpose of illustrating the intended environment of the claimed design and form no part of the claimed design.
